(57) **CLAIM**

The ornamental design a lid for a beverage container, as shown and described.

DESCRIPTION

FIG. 1 is a top perspective view of a lid for a cup showing the novel lid design.

FIG. 2 is a front side view, taken looking at the front of the lid design.

FIG. 3 is a back side view, taken looking at the back of the lid design.

FIG. 4 is a left side view, taken looking at the left side of the lid design.

FIG. 5 is a right side view, taken looking at the right side of the lid design.

FIG. 6 is a top plan view taken looking down at the top of the lid design.

FIG. 7 is a bottom plan view taken looking up at the underside of the lid design; and,

FIG. 8 is a bottom perspective view of a lid for a cup, looking up at underside of the novel lid design.

In each of the drawing figures, the broken lines showing the remainder of the lids, or portions thereof, are directed to the environment in which the design is utilized. The portions of the design that are shown in broken lines depict environmental subject matter only and form no part of the claimed design.

1 Claim, 3 Drawing Sheets
